(57) **CLAIM**

The ornamental design for a medical test cartridge, as shown and described.

DESCRIPTION

FIG. 1 is a perspective view of the ornamental design for a medical test cartridge made of light-transmitting material with a cap opened, as seen from the front, top side; FIG. 2 is a front elevational view thereof, the bottom elevational view being mirror symmetrical;

FIG. 3 is a left elevational view thereof;

FIG. 4 is a right elevational view thereof;

FIG. 5 is a top plan view thereof;

FIG. 6 is a bottom plan view thereof;

FIG. 7 is a perspective view of the ornamental design for the medical test cartridge made of light-transmitting material with the cap closed, as seen from the front, top side;

FIG. 8 is a front elevational view thereof, the bottom elevational view being mirror symmetrical;

FIG. 9 is a left elevational view thereof;

FIG. 10 is a right elevational view thereof;

FIG. 11 is a top plan view thereof; and,

FIG. 12 is a bottom plan view thereof.
